UNITED STATES PATENT OFFICE.

CHARLES HENRY HEIMLICH, OF VENICE, OHIO.

NECK-YOKE COUPLING.

SPECIFICATION forming part of Letters Patent No. 593,578, dated November 16, 1897.

Application filed February 6, 1897. Serial No. 622,241. (No model.)

To all whom it may concern:

Be it known that I, CHARLES HENRY HEIMLICH, a citizen of the United States, residing at Venice, in the county of Erie and State of Ohio, have invented certain new and useful Improvements in Neck-Yoke Couplings; and I do hereby declare the following to be a full, clear, and exact description of the invention, such as will enable others skilled in the art to which it appertains to make and use the same.

My invention relates to improvements in devices for attachment to vehicles and which are designed to automatically operate to prevent the detachment of the neck-yoke from the pole or the horse from breaking loose and running away should the doubletree become unhooked or the tugs, the whiffletree, or other parts of the vehicle or harness become broken or unfastened.

To these ends my invention comprises certain details of construction and arrangement of parts whereby the above results are attained, as will be hereinafter fully described, and specifically defined in the appended claim.

In the accompanying drawings, Figure 1 represents a perspective view of the forward end of the tongue or pole of an ordinary two-horse vehicle with my invention applied thereto. Fig. 2 is an enlarged detail perspective view of my invention.

Similar reference-numerals represent corresponding parts in both figures of the drawings.

1 represents the pole or tongue of any ordinary two-horse vehicle, 2 the neck-yoke, and 3 the ring connected to the yoke and which engages the pole or tongue in the usual manner. Upon the under side of the pole or tongue and immediately in advance of the said ring 3 when in its proper position on the pole I secure a screw-eye 4, to which is pivotally connected a bell-crank catch comprising a finger 5 and an extension 6, arranged at right angles thereto, the purpose of such extension being to bear against the under side of the pole or tongue to prevent any forward movement of the finger 5 when the latter is in a vertical position.

In practice I construct the finger 5 of greater

weight than the extension 6, so that the former will occupy a vertical position. As the ring of the neck-yoke is being placed upon the pole or tongue it will engage and force the finger 5 rearward and upward as it passes 55 the pivotal point, and the continued movement of the ring will bring it beyond the extreme free end of the finger 5, when said finger by its own weight will instantly fall back to its perpendicular position, in which position the removal of the ring of the neck-yoke from engagement with the pole or tongue is absolutely prevented. When it is desired to remove the ring, the finger 5 is raised again by hand, so as to allow said ring to pass forward under it. Thus if the traces should become detached or the doubletree, singletree, or any part of the harness become broken or unfastened the finger 5 will hold the neck-yoke in its position upon the pole or tongue 65 by reason of the usual hame-tug connections between it and the collar and thus prevent the horse from becoming detached from the vehicle.

So far I have described my invention as applied to a two-horse vehicle, the same being clearly shown in Fig. 1, but it will be readily understood that it can be applied to one-horse vehicles with equal advantage, in which event, however, it will be necessary to arrange one of the locking-fingers upon each shaft, so that should the traces become detached, the whiffletree broken, or other parts of the harness disconnected the shaft-tugs will be brought into contact with the fingers 80 85 5 and thus prevent the horse from passing out from the shafts.

It will be seen from the foregoing that my invention provides in a very simple inexpensive manner a device which will effectually 90 prevent accidents or runaways resulting from the causes above referred to, and it is obvious that modifications may be made without departing materially from the spirit and scope of my invention, and I reserve the right 95 so to change it.

Having thus described my invention, what I claim, and desire to secure by Letters Patent, is—

The combination with a pole-shaft of a ve- 100

hicle, of a screw-eye attached to the under portion thereof, and a bell-crank catch mounted in said eye and comprising an extension adapted to engage the under side of the pole 5 and a weighted finger normally gravitating in a vertical plane, and a neck-yoke having a ring, substantially as and for the purposes specified.

In testimony whereof I have signed this specification in the presence of two subscribing witnesses.

CHARLES HENRY HEIMLICH.
